UNITED STATES PATENT OFFICE.

HARRY E. ESSIG, OF CANTON, OHIO, ASSIGNOR TO THE ESSIG PIVOT WINDOW COMPANY, OF CANTON, OHIO, A CORPORATION.

REVOLVING-WINDOW STRIP.

SPECIFICATION forming part of Letters Patent No. 728,690, dated May 19, 1903.

Application filed December 4, 1902. Serial No. 133,861. (No model.)

To all whom it may concern:

Be it known that I, HARRY E. ESSIG, a citizen of the United States, residing at Canton, in the county of Stark and State of Ohio, have 5 invented a new and useful Improvement in Revolving-Window Strips, of which the following is a specification.

My invention relates to the strips to which a revolving window-sash is pivoted on each 10 side; and the object of my improvement is to make the strips so the ends will bend or curve inward, and thus fit closely against the side edges of the window-sash throughout its 15 length. I attain this object by the construction illustrated in the accompanying drawings, in which—

Figure 1 is an elevation of a window-sash and part of the frame with the frame-strips removed on the near side and the sash broken 20 away to show the pivot on one side; Fig. 2, a similar view showing the sash turned part way on its pivot; Fig. 3, a fragmentary view showing the detail of the pivotal connection; Fig. 4, a fragmentary perspective view of the 25 sash and strip and pivotal connection, showing the manner of bending or curving the strip; and Fig. 5, a cross-section of the sash side bar and the adjoining strips.

In this type of window the sash 1 is pivoted 30 on its horizontal axis to the strips 2, and the adjoining faces of the sash and the strips are corrugated or grooved, as at 3, so that when the strip is closed in its normal position against the sash these corrugations or grooves 35 engage each other, as shown in Fig. 5.

In the pivotal connection 4 of the sash with the strip is provided a spring, as 5, which permits the strip to be forced away from the sash by the rotation of the latter, the sash-strips being held by the frame-strips 6, thereby 40 disengaging the corrugations or grooves and permitting the rotation of the window-sash on its pivots.

The spring 5 acts to hold the strip closely 45 against the sash at or near the pivotal point at all times, and various devices have been used to hold the ends of the strips closely against the sash when the sash and strips are joined lengthwise. Among the methods of accomplishing

this is by forming the strips so they will bend 50 or curve inward at either end, by which bending or curving they are always held in close contact with the edge of the sash when the middle of the strip is forced against it by action of the spring 5 or otherwise. It has been 55 usual to so form the strips by sawing or cutting them in a curve or by merely bending them in that direction; but it has been found that a strip so formed will not hold its curve and will therefore cease to be effective. 60

I bend or curve the strip by cutting one or more wedge-shaped notches 7 across the outer side and by forcing or pressing into these notches similarly-shaped and slightly larger wedges 8, which act to bend or curve the 65 ends of the strip inward. One or more of these notches and wedges are preferably used either way from the central or pivotal point of the strip. The wedges 8 retain their places in the notches by friction, or glue can be 70 used to increase the adhesion; but to more positively hold the wedges in position the staples 9 are preferably driven into the strip astride of the wedges. By the use of these expanding wedges there is a positive bend or 75 curve given to the strip which cannot be overcome except by permanently disturbing the natural resiliency of the wood.

What I claim as my invention, and desire 80 to secure by Letters Patent, is—

1. A window-strip, wedge-shaped notches across said strips, and slightly larger similarly-shaped wedges forced or pressed into said notches, thereby bending or curving said strip. 85

2. A window-strip, wedge-shaped notches across said strip, slightly larger similarly-shaped notches forced or pressed into said notches and staples driven into said strip astride of the wedges. 90

In testimony whereof I have signed my name to this specification in the presence of two subscribing witnesses.

HARRY E. ESSIG.
